UNITED STATES PATENT OFFICE.

JOSEPH C. KUCEWICZ, OF CLEVELAND, OHIO.

HAIRPIN.

Application filed July 31, 1922. Serial No. 578,682.

To all whom it may concern:

Be it known that I, JOSEPH C. KUCEWICZ, a citizen of the United States, residing at Cleveland, in the county of Cuyahoga and 5 State of Ohio, have invented certain new and useful Improvements in Hairpins, of which the following is a specification.

This invention relates to hair pins, and has for its object to provide a hair pin which 10 will not become loose and accidentally fall out and which when used will serve to crimp the hair, the construction being such that when the hair pins are pushed in the hair they will tend to turn or twist around and 15 in this way lock themselves in the hair so that they will not fall out, and as they are pulled out of the hair they have a twisting motion in reverse. These results are accomplished by making a spiral in each branch 20 of the hair pin, these spirals being coiled around the axis of each branch, and the spirals not being coiled around each other as has been proposed.

In the accompanying drawings, Figure 1 25 is an elevation of a hair pin embodying the invention; Fig. 2 is an elevation of the same turned vertically at 90°; Fig. 3 is a plan view of the position shown in Fig. 1; Fig. 4 is an elevation of a modified form of hair 30 pin in which the helixes of the arms are wound oppositely; Fig. 5 is a fragmentary view of the same turned vertically at 90°; Fig. 6 is a plan view of the position shown in Fig. 4.

35 Referring specifically to the drawings, the hair pins shown consist of two branches 6 and 7 connected at the rear end by a bend 8. Adjacent the bend, the two branches are located in the same plane, forming what may 40 be called or regarded as a handle portion. Beyond this the branches diverge from said plane, as shown in Fig. 1, so that the points 9 are spaced from each other in a plane at a right angle to the plane of the handle portion. 45 Each branch is coiled to form a helix, as indicated at 10, and the convolution or curvature of each helix is in the form shown in Fig. 1 in the same direction around its respective axis. In the form shown in Fig.

4 the helices are wound oppositely. In the 50 short hair pins the coils are rather higher pitch than those in the long hair pins.

When the hair pin so constructed is pushed into the hair the helical construction 55 of the branches causes a twisting action which tends to crimp or twist the hair around the branches and to draw the branches toward each other, which has the effect of giving a wavy appearance to the hair and also fastens the pin in the hair so 60 that it will not accidentally fall out, but may be withdrawn by a slight pull or special effort which will cause the same to untwist or turn in the reverse direction. Fig. 2 illustrates a position assumed by the branches 65 of the pin under a drawing action incident to placing the pin in the hair.

An important feature of this pin is that 70 when it is pushed into the hair it does not have to be rotated by the wearer, the structure being such that it rotates itself while being pushed in the hair. I am aware that the patent to Fosnight No. 811,628 shows a 75 somewhat similar hair pin, which, however, may be forced into the hair by proper pressure together with a slight rotation, and may be withdrawn by rotating it, but this is objectionable and inconvenient for the operator. By means of the present construction no positive rotation is required at the 80 hands of the operator, as all that is necessary is to force it into the hair when it will contract and rotate itself and when so pushed in it locks itself and cannot fall out.

I claim:

A hair pin having two branches and a connecting bend, the branches extending from the bend with straight portions located in a single plane, both branches being coiled in the same direction to form helices 90 on different axes, which axes diverge from the plane of the straight portions.

In testimony whereof, I affix my signature in presence of two witnesses.

JOSEPH C. KUCEWICZ.
